Des. 195,187
Patented May 7, 1963

195,187

QUILTED PLASTIC SHEET MATERIAL

Irvin S. Kramer, Lynbrook, N.Y., assignor to The Barr Corporation, Richmond Hill, N.Y.

Filed Oct. 20, 1961, Ser. No. 67,191

Term of patent 14 years

(Cl. D87—3)

FIG. 1

FIG. 2

FIG. 3

FIG. 4

FIG. 1 is a plan view of a quilted plastic sheet material showing my new design;

FIG. 2 is a section taken through the line 2—2 of FIG. 1;

FIG. 3 is a section taken through the line 3—3 of FIG. 1; and

FIG. 4 is a section taken through the line 4—4 of FIG. 1.

I claim:

The ornamental design for a quilted plastic sheet material, substantially as shown.
